UNITED STATES PATENT OFFICE.

ELLSWORTH GRAY, OF HOUSTON, TEXAS.

PUMP.

Application filed January 5, 1925. Serial No. 520.

To all whom it may concern:

Be it known that I, ELLSWORTH GRAY, a citizen of the United States, residing at Houston, Harris County, Texas, have invented a certain new and useful Improvement in Pumps, of which the following is a specification.

My invention relates to an improvement in pumps particularly adapted for deep well work, and is further intended to operate in handling liquids containing a certain amount of sand or other sediment tending to wear the pump.

It is an object of the invention to provide a pump construction in which the ordinary standing valve or foot valve will be dispensed with, the function of the foot valve being served by a sliding valve within the pump barrel.

Another object is to provide a pump construction to which sand or sediment will not easily find access, and to provide for the settling out of whatever foreign matter may enter the pump barrel.

Another object is to provide a self contained pump construction which may be easily withdrawn from the well if necessity arises, but in which little wear may occur, thus tending to allow it to remain in the well for long periods of time. These and other objects and advantages will be more specifically referred to in the specification as follows:

Referring to the drawing, Fig. 1 is a central longitudinal section through the lower end of the pump barrel constructed in accordance with my invention. Fig. 2 is a transverse section on the plane 2—2 of Fig. 1. Like numerals of reference are applied to like parts in all the views.

In the drawing the pump barrel 1 is shown as being connected to a coupling 2 by means in which it may be attached to tubing in the usual manner, said tubing not being shown. The pump barrel 1 is formed with a single wall adjacent its upper end, but this wall is provided with an outer wall 2 connected to the inner wall at 3, as shown in the drawing. While this connection is shown as an integral one, it is obvious that any preferred form of connection between the two walls of the working barrel may be employed. The inner wall, which may be designated as 4, is continuous from its upper end to the lower end to form an inner cylindrical surface in which the

plunger may operate. The outer wall is spaced from the inner wall to provide an upper chamber 5 and a lower chamber 6, these two chambers being separated by a partition 7. The lower end of the outer wall 4 is closed, as shown at 8, to prevent the inlet of fluid at that end.

The inner wall 4 of the working barrel is provided with a plurality of openings 9 leading to the chamber 5, and another series of openings 10 spaced slightly below the partition 7, and connecting the inside of the working barrel with the chamber 6; the upper wall is also provided with a plurality of openings 11 at a point spaced slightly above the openings 9 in the inner wall.

The plunger which I contemplate employing is formed with a tubular head 12, which is reduced somewhat in diameter at the upper end to form a seat 13 for packing cups 14 spaced apart by the usual spacing rings 15, a nut 16 at the upper end of the plunger serving to hold the cups and spacing rings removably in position. The upper end of the plunger is closed except for a plurality of openings 17 to allow the passage of oil or other liquid upwardly into the working barrel. The said upper end is provided with a threaded shank 18 by means of which it may be connected to a pump rod 19.

The lower end of the plunger head 12 is threaded internally at 20 to receive a lower section 21 of slightly smaller diameter. The lower end of the head 12 thus forms a shoulder 22 to limit the upward movement on the member 21 of a valve ring 23. The downward movement of said valve ring relative to the member 21 is limited by an upper shoulder 24 formed upon a valve housing 25 which is screwed upon the lower end of the plunger member 21. The valve housing 25 is formed with a chamber 26 therein at the lower end of which a seat 27 is formed for a valve 28 of ordinary construction. The passage 29 below the said valve is smaller in diameter than the valve chamber, as clearly shown in the drawing. The upward movement of the valve is adapted to be limited by a transverse pin 30 extending diametrically across said chamber at a point spaced above the valve. The outer diameter of the valve housing 25 is reduced to provide a seat for packing rings 31 and spacers indicated at 32, similar to those described at the upper end of the plunger,

said packing means being held in position by the nut 32 in the lower end of the valve housing.

In operation, the device will be positioned 5 in the lower end of the well at any desired point so that it is submerged in the liquid. At the downward stroke of the plunger the shoulder 22 will contact with the ring 23 which fits closely within the working barrel, 10 and will force the said valve ring downwardly, thus exposing the openings 9 and 10, and allowing the passage of liquid through the openings into the chamber 6, as indicated by the arrows.

15 On the upward stroke of the plunger therefore, the suction exerted by the packing means 31 will draw the liquid in through said openings to fill the chamber 6, and the space within the lower end of the working 20 barrel. At the extreme upper end of the upward stroke the shoulder 24 upon the valve housing will contact with the valve ring and move it upwardly to close the openings 9 and 10, thus shutting off the further 25 inlet or outlet of liquid.

On the downward stroke thereafter, the ring will remain in position covering said openings through the frictional engagement of said ring with the inner wall 4 of the 30 pump barrel. The valve 23 is maintained against movement, until acted upon by the shoulders 22 or 23 of the plunger, by the action of friction between the valve and the pump barrel, aided somewhat by the viscosity 35 of the oil between the same, said oil coming from the well which is being pumped. Such fluid as finds entrance to the space above and below the valve is largely gas or air and, being compressible, has insufficient 40 force to move the valve unduly before the plunger engages with said valve. The fluid therefore, which is drawn within the lower end of the chamber 6 of the pump barrel, as previously described, will be forced up- 45 wardly past the valve 23 toward the surface. When the plunger has nearly reached the lower end of its stroke the shoulder 22 will contact with the valve ring 23 and force it downwardly to expose the openings, the 50 parts assuming approximately the position shown in the drawing. The cups 14 at the upper end will assist in raising the fluid upwardly toward the surface and also prevent the liquid from passing backwardly 55 into the working barrel, in an obvious manner.

As the inlet openings 11 are spaced upwardly from the bottom of the well, there will be only a slight tendency for sand or 60 sediment being drawn inwardly with the oil or other liquid, and for that reason very little trouble with foreign matter of this kind will be experienced. Such sand or sediment as does find access through these pass- 65 sages will have an opportunity of settling

into the lower end of the chamber 6, and will not therefore tend to wear the plunger or working barrel to any great extent. The valve ring 23 has only a slight movement 70 in the operation of the pump, and will not be subject to material wear. It will therefore serve its purpose for a materially longer period than will the ordinary standing valve, and will be a source of great economy in the operation of the pump. 75 Furthermore, if wear occurs in the pump plunger, the said plunger and the valve ring thereon will be easily withdrawn to the surface without the necessity of withdrawing the working barrel, as is the case where the ordinary standing valve is to be repaired. 80

If however it becomes necessary to withdraw the tubing and working barrel, the fact that the openings 9 and 11 are not closed, will allow the fluid to drain from the 85 barrel as the said barrel is raised and thus prevent waste of the oil in the tubing and make it much easier and cleaner to handle the pipe as it is withdrawn.

It will be obvious that the construction 90 herein shown may be modified in various ways without departing from the spirit of the invention. I do not therefore wish to be limited to the exact manner in which the parts are connected or assembled further 95 than comes within the scope of the appended claims.

What I claim as new, and desire to protect by Letters Patent is:

1. In a pump, a pump barrel having an inner wall open at its lower end, an outer wall spaced from the inner wall of the pump barrel, a partition closing the space between the said walls at an intermediate point, the lower end of the outer wall being closed, said outer and inner walls having openings therein above the intermediate partition, the inner walls having lateral openings below said partition, a pump plunger, a valve ring slidable on the lower portion of said pump plunger, means to limit the movement of said ring on said plunger, whereby the openings in the inner wall of the working barrel below said partition will be closed during the greater portion of the downward stroke of the plunger and be open during the greater portion of the upward stroke, in the manner described. 110

2. A pump of the character described, comprising a pump barrel, an outer wall spaced therefrom and enclosing the larger portion of said pump barrel, a partition connecting said barrel and said outer wall intermediate its ends, there being openings in said wall and pump barrel above said partition, and an opening in said barrel below said partition, a pump plunger within said pump barrel, and a valve sleeve between said plunger and barrel adapted to close the opening in said pump barrel below said 120 125 130

partition during the greater part of the down stroke and to open during the greater part of the up stroke, in the manner described.

- 5 3. In a pump of the character described, a pump barrel, a plunger therein, a valve ring slideable on said plunger within said barrel, packing means on said plunger above and below said ring, said ring adapted to
10 close the passages of liquid from said pump barrel on the down stroke and permit entrance of liquid thereto on the up stroke.
4. In a pump of the character described, a pump barrel, a wall attached to said barrel adjacent the upper end and enclosing the lower end of said barrel, a plunger slideable in said pump barrel, a sliding ring thereon, packing means on said plunger above and below said ring, there being openings in
15 said wall and said pump barrel controlled by the movement of said ring in the manner described.
5. In a pump of the character described, a pump barrel, a wall spaced from said bar-
- rel and enclosing the lower end thereof, a plunger in said pump barrel, said wall and said pump barrel having openings for the admission of liquid, a ring on said plunger and controlled by the movement of said plunger to open and close said openings in
20 the manner described, and a partition connecting said barrel and wall adjacent said openings.
6. In a pump, a pump barrel, a pump plunger therein, packing means at each end of said plunger the intermediate portion being spaced from said barrel, a valve ring on said intermediate portion, there being upper and lower openings in said pump barrel for the admission of liquid, a housing enclosing the lower end of said pump barrel and the lower of said openings, and means on said plunger to move said ring to close
25 said openings as desired.

In testimony whereof I hereunto affix my signature this 12th day of December, A. D. 1924.

ELLSWORTH GRAY.
